TENSION MECHANISM FOR WINDING
MACHINES

Vernon H. Meyer, Beverly, Mass., assignor to
Sibley-Pym Corporation, Lynn, Mass., a cor-
poration of Massachusetts

Application July 8, 1936, Serial No. 89,587

12 Claims.

(Cl. 242—3)

This invention relates to machines for use in manufacturing cores for golf balls or similar wound articles and consists in a novel tension mechanism constructed and arranged to deliver the thread being wound upon the core continuously under uniform tension and controlled condition of elongation. For example, in winding a golf ball core from an elastic thread it is important to control both the percentage of elongation imparted to the thread and the tension under which the thread is wound in order to meet the specifications laid down for the particular balls being manufactured. The hardness and resiliency of the core depend upon these factors, while the symmetry and homogeneity of the core structure depend upon their being maintained without variation during the winding process. The mechanism of the present invention is designed to meet these exacting conditions and to provide a compact and reliable construction which may be depended upon to act uniformly under the more or less unfavorable conditions of commercial manufacture.

One troublesome variation sometimes encountered in the condition of thread supplied to the core is occasioned by the catching of the thread at one end or other of the supply reel. When this happens an increased initial tension occurs in the thread and, if not corrected, this results in non-uniform winding or in breaking of the thread. The mechanism herein shown is designed to compensate for such temporary irregularities by releasing the retarding pressure to which the thread is subjected in passing through the mechanism. On the other hand, if the initial tension in the thread reaching the core is temporarily lowered for any reason the retarding feed of the tension mechanism is correspondingly and instantly increased.

From one standpoint the salient feature of the invention consists in a dance lever arranged continuously to weigh or measure the tension of the thread in passing to the rotating core and to control by its movement in weighing or measuring the tension therein the retarding pressure to which the thread is subjected. Preferably this mechanism is utilized in part to effect a definite predetermined elongation of the thread under tension. As herein shown the mechanism includes a pair of driven rolls which are geared together to operate upon the thread with an increasing ratio of peripheral speed and the thread is retarded and tensioned by being adjustably pressed against the first or slower moving roll of the pair. The dance lever above mentioned is

arranged to control this pressure upon the thread in such a manner as momentarily to permit an increment of forward slip to enter the rate of travel of the thread and thus to compensate for temporary increases in elongation or tension. 5

As herein shown a thread-driven roll is mounted concentrically with respect to a support upon which the cooperating gear-driven roll of the set is mounted and provision is made for rotatably adjusting the support to vary the length 10 of wrap of the thread about the roll and so control the slip thereof. The mechanism also includes an oscillatory pressure arm having cam connection with the dance lever and novel provision is made for adjusting the pressure roll 15 which the arm carries to regulate the position of the arm. It is thus possible to secure a fine adjustment and setting of the whole mechanism to insure uniform action to a high degree of response to variations in working conditions. 20

In another aspect the invention consists in novel thread-elongating and tensioning mechanism adapted for use in a winding machine of the general type disclosed in U. S. Letters Patent No. 2,033,356 granted March 10, 1936, on an application of Arthur F. Pym. For purposes of illustration I have shown the mechanism of my invention as embodied in a machine otherwise similar to the winding machine disclosed in that patent. 30

The features of the invention above discussed and others will be best understood and appreciated from the following description of a preferred embodiment thereof selected for purposes of illustration and shown in the accompanying 35 drawings in which,

Fig. 1 is a view of the mechanism in front elevation.

Fig. 2 is a sectional view on the line 2—2 of Fig. 1, and

Fig. 3 is a rear view of the gear connections of the mechanism.

In the drawings only so much of the machine is shown as is needed for a complete understanding of the tension mechanism and for further 45 details of construction reference may be had to the patent above identified.

The winding machine has a main frame which includes a vertical panel 10 from which project forwardly a pair of rolls 11 and 12 arranged 50 horizontally side by side. An endless elastic apron 13 extends about the two rolls and cooperates with them to support and cradle the core 20 which is to be wound of an elastic thread 19. One or both of the rolls may be driven thus 55

imparting movement to the apron 13 which in turn exerts peripheral traction on the core 20 so that it is rotated at uniform peripheral speed regardless of its diameter. The core is maintained in place by a detector roll 14 having a convex rim and arranged to run freely on the upper side of the core 20, as the latter is rotated. The detector roll is journaled in the free end of an arm 15 extending horizontally across the front of the panel 10 and pivotally mounted on a shaft 16. It will be seen that as the diameter of the core 20 increases under the winding operation the arm 15 will be gradually swung upwardly about its axis. The detector roll also functions to maintain the core spherical in shape by reacting with the last wound turns of the thread to displace the core transversely to the winding plane.

The elastic thread is supplied to the winding machine from a reel 17 rotatably mounted upon a standard 18 at a point above the panel 10. The thread is led downwardly to the tension mechanism, organized to impart a predetermined stretch and tension to it, and then upwardly over a tension measuring roll which directs it to the core 20.

Part of the tension mechanism is mounted upon a circular flanged panel 21 which is set into the face of the vertical panel 10 and adjustably retained in place by clamping plates 32 which engage segmental ribs 33 on its rear face as shown in Fig. 3. The circular panel 21 is formed with a cylindrical hub or casing 22 in which are journaled three horizontal parallel shafts each equipped with its own set of ball bearings, as best shown in Fig. 2. Of these, the shaft 23 is arranged substantially at the center of the circular panel 21. It projects forwardly and has keyed to its outer end a cylindrical steel roll 24. The elastic thread 19 is led directly to this roll in passing downwardly from the reel 17. It passes about slightly less than 90° of its circumference, when the panel is adjusted as shown in Fig. 1, and is then led about the circumference of a second roll 27 mounted on the outer end of a shaft 26 which is journaled in the boss 22 slightly below and to the left of the shaft 23 as seen in Fig. 1.

At its rear end, the shaft 23 carries a large gear 25 and this meshes with a pinion 30 pinned to the rear end of a shaft 29 which is journaled in the lower portion of the casing 22 beneath the shaft 23 and projects rearwardly. The shaft 29 carries also a gear 31 which in turn meshes with a pinion 28 fast to the rear end of the shaft 26 which carries the roll 27 already referred to. The gear ratio is such that the roll 27 is positively driven at a greater speed than the roll 24, so that in passing about the circumference of these two rolls, a positive predetermined amount of elongation is imparted to the elastic thread 19. The amount of this elongation may be regulated and adjusted in accordance with the requirements of the work in hand by varying the gear ratio. As herein shown the ratio is 1:8, the elastic thread being therefore stretched to eight times its initial length in passing about the rolls 24 and 27 on its way to the winding point.

The elastic thread 19 is maintained in engagement with the roll 24 by a pressure roll 35, preferably rubber covered, which is rotatably mounted in the forward end of a slide 36 adjustably carried in an upwardly extending arm 39 which is pivotally mounted on a stud 40 near the lower edge of the panel 10. The slide 36 may be adjusted horizontally upon the arm by means of an

adjusting screw 38 and is arranged to be locked in adjusted position by a threaded clamping screw 37 provided for convenience with a finger lever. The arm 39 also carries a wire thread guide loop 42 through which the elastic thread 5 passes in arriving at the bight of the rolls 24 and 35. A tension spring 41 tends at all times to swing the lever 39 toward the left and to press the roll 35 against the roll 24 and the interposed thread 19.

The position of the arm 39 and also the pressure of the roll 35 is regulated in part by a cam carried at the upper end of the arm 39. This comprises a plate having a projecting cam flange 43, the plate being connected to the arm by a pivot 44, and being provided with a curved slot for a threaded clamping member 45 also provided with a finger lever. By loosening the clamping member the cam may be rocked about the pivot 44 to the desired position of adjustment, and for the purpose of determining this, an index scale is provided upon the surface of the arm 39. The cam 43 cooperates with a cam roll 50 which is freely rotatable upon the right hand end of a dance lever 51 fast to the forward end of a shaft 52 journaled in a boss 53 secured to the panel 10. At its left hand end the dance lever 51 carries an idle roll 54 over which the thread 19 passes in a loop after it leaves the second or elongating roll 27 of the tension mechanism. The cam 43 is so positioned upon the arm 39 that when the dance lever is rocked in a counter clockwise direction the arm 39 is swung outwardly tending to release the pressure upon the thread 19, and thereby to reduce the tension therein. When the tension is reduced the dance lever 51 tends to rock in a clockwise direction, and the cam roll 50 moves downwardly permitting the arm 39 to swing inwardly and again increase the tension on the thread 19.

The movement of the dance lever 51 is damped by a dash-pot mechanism connected with the shaft 52 through an arm 55 which is pinned to its rear end. Pivotally connected to the arm 55 is a rod 56 which extends downwardly into a dash-pot 57. The arm 55 also extends upwardly where it is provided with an adjustable stop 58 arranged to engage with a lug projecting from the back of the panel 10 and limiting the movement of the dance lever.

From the foregoing description it will be seen that I have provided a self-contained tension mechanism operating to deliver an elastic thread to the winding point with a predetermined degree of elongation and under uniform tension. The roll 24 is rotated by the passage about it of the moving thread 19 and that in turn drives the second or elongating roll 27 through gearing which steps up the peripheral speed of the roll 27 in an 8:1 ratio with respect to the roll 24, or whatever ratio may be required in view of the hardness of core desired. Since the elastic thread is normally wrapped about a substantial arcuate portion of the rolls 27 and is pressed against the roll 24 by the pressure roll 35 there is a negligible amount of slip between the thread and the respective rolls and the elongation imparted to the thread corresponds closely to the ratio of their peripheral speeds.

The peripheral speed at which the core 20 is 70 rotated by the apron 13 is equal to or slightly in excess of the peripheral speed of the roll 27 so that the core is wound with thread which is maintained under the full elongation imparted to it by the rolls 24 and 27 and normally under the 75

full tension required to rotate the roll 24 and drive the gear train related thereto. This tension, however, is weighed or measured and continuously balanced at a uniform value by the action of the dance lever 51. The lever 51 measures or weighs the tension in the thread passing to the core in that the lever movement is proportional to the tension in the thread. The higher the tension in the thread the lower moves the left-hand end of the lever and vice versa. The lever not only measures or weighs the tension in the thread at each instant during the operation of the machine, but visually indicates by its position the amount of tension existing from second to second. If for any reason the tension of the thread as delivered to the core rises, as perhaps on account of temporary checking of the supply reel, then the dance lever is pulled down at its left end by the bight of the thread and, as its right end rises, the arm 39 is swung toward the right and the pressure of the roll 35 upon the thread is relaxed permitting an increment of forward slip to enter its rate of travel, with the resulting decrease in both elongation and tension. In other words, the roll 24 does not, under these circumstances, hold back the travel of the thread to its own rate of peripheral speed but permits it to travel at a slightly faster rate. Immediately the tension is reduced in this manner the dance lever is allowed to rock in a clockwise manner and the cam permits the arm 39 to swing toward the left, thus increasing the pressure of the roll 35 upon the thread and reducing its slip upon the roll 24. This balancing action continues constantly during the operation of the machine with the result that the tension of the thread is maintained uniformly throughout the winding operation.

The action of the mechanism above described may be regulated, controlled and adjusted by various means which will be now enumerated. In the first place the vibrations of the dance lever 51 is damped by the action of the dash-pot 75 through the rod 56 and the limiting position of the lever in its clockwise movement is adjustably determined by the stop screw 58. The range of movement of the cam roll 50 is thus maintained at all times within the amplitude of the cam 43 so that the spring 41 is always effective in tending to rock the dance lever in a clockwise direction. The cam 43 itself as already explained is angularly adjustable upon the arm 39 and may be positioned so that the displacement of the arm 39 and its pressure roll may be effected more or less rapidly for any given movement of the dance lever. Further, the rubber covered pressure roll 35 is adjustably mounted upon the arm 39 so that this may be brought into proper bearing with respect to the roll 24 when the arm 39 occupies the proper angular position to present its cam 43 to the cam roll of the dance lever. Finally the circular panel 21 may be adjusted angularly in the machine in such a manner as to vary the arc of wrap of the thread 19 about the circumference of the roll 27. For example, the clamping plates 32 may be loosened and the panel 21 rotated in a clockwise direction to move the roll 27 upwardly with respect to the roll 24 and so increase the angle of wrap about the roll 24, it being understood that the roll 24 is journalled concentrically in respect to the axis of the panel 21. By means of all these various provisions the action of the described mechanism may be regulated to a nicety and any desired condition of elongation and tension may be secured.

Many modifications and changes in detail will readily occur to those skilled in the art without departing from the spirit and scope of my invention and having shown and described an illustrative construction embodying the features thereof, what I claim as new and desire to secure by Letters Patent of the United States is,

1. In a golf ball winding machine having core-rotating mechanism and a thread supply, tension mechanism including a thread-driven roll, a thread-elongating roll geared thereto, a pressure roll for pressing the thread against said driven roll, and a tension measuring lever responsive to the tension of the thread and arranged to control by its movement the position of the said pressure roll.

2. In a golf ball winding machine having core-rotating mechanism and a thread supply, tension mechanism including a rotatably adjustable supporting member carrying thread-driven elongating rolls geared together to rotate at different speeds, a pressure arm arranged to engage the thread against one of said elongating rolls, and a tension measuring lever responsive to the tension of the thread and having cam connection with said pressure arm, said supporting member being rotatable to vary the wrap of the thread about one of said elongating rolls.

3. In a golf ball winding machine having core-rotating mechanism and a thread supply, tension mechanism including a rotatably adjustable support having a thread-driven roll journaled therein concentrically with respect to its own axis of rotation, a thread-elongating roll geared to the first mentioned roll and mounted eccentrically in said support, and means for holding the support in different positions of angular adjustment with said rolls in different relative positions with respect to each other.

4. In a golf ball winding machine having core-rotating mechanism and a thread supply, tension mechanism including a thread-driven roll, an arm carrying a pressure roll for pressing the thread against said driven roll and having a cam, and a dance lever movable for measuring the tension in the thread as it passes to the core and having a cam roll arranged to run on the cam of said arm.

5. In a golf ball winding machine having core-rotating mechanism and a thread supply, tension mechanism including cooperating thread-retarding rolls yieldably pressed together, a cam operated lever for separating said rolls, and a dance lever movable for measuring the tension in the thread and having an adjustable cam connection with said cam operated lever.

6. In a golf ball winding machine having core-rotating means and a thread supply, thread tensioning and elongating mechanism including a pair of geared thread-engaging rolls rotatable at different peripheral speeds to elongate the thread, a bodily movable pressure roll for retarding the thread by engaging it against one of said geared rolls, and a tension weighing device acted upon by the thread and movable for releasing the pressure of the pressure roll when the tension in the thread exceeds a predetermined degree.

7. In a golf ball winding machine having core-rotating means and a thread supply, tension mechanism including a thread retarding roll, an oscillatory arm having a pressure roll arranged to engage said retarding roll, means including a lever movable in response to variations in the thread tension for controlling the position of said

arm, and means for adjustably supporting said pressure roll upon said arm.

8. In a winding machine having core rotating means and a thread supply, a rotatable panel having a pair of geared rolls journaled therein, one of which is concentric in the panel, an oscillatory arm mounted outside said panel and having a pressure roll adjustably mounted thereon for engagement with the concentric roll in the panel, and a vibratory lever having a guide roll for engaging the bight of the thread as it passes from the geared rolls to the core and having also a cam connection with said oscillatory arm.

9. In a winding machine having core rotating means and a thread supply, a rotatable panel having a roll mounted thereon which is concentric in the panel and a second thread roll which is eccentrically mounted on the panel, an oscillatory arm mounted outside said panel and having a tension-controlling roll mounted thereon, and a vibratory lever having a guide roll for engaging the bight of the thread as it passes from the eccentrically mounted roll on the panel to the core and having also an operative connection with said oscillatory arm.

10. A winding machine having core rotating means and thread supplying mechanism including thread-elongating rolls located below the core, a

tension-measuring lever having a thread guide roll located above the core so that thread passes downwardly therefrom to the core, and an arm carrying a pressure roll for engaging the thread against one of said thread-elongating rolls and a cam located above said rolls in position to be acted upon by the tension-measuring lever.

11. A winding machine having core rotating means and a thread supply, tension mechanism including a thread retarding roll, an oscillatory arm having a pressure roll arranged to engage said retarding roll adjustably mounted thereon and a cam surface located adjacent to its free end, means including a tension measuring lever engaged by the thread as it passes from said pressure roll to the core being wound and acting upon said cam surface for controlling the position of said arm and the pressure roll thereon.

12. A golf ball winding machine comprising a thread supply reel, core-rotating means, thread elongating means located between said supply reel and said rotating means, thread tensioning means, and means responsive to changes in the tension of the elongated thread located between said elongating means and said core-rotating means for adjusting said tensioning means.

VERNON H. MEYER.
